Des. 240,631
Patented July 20, 1976

240,631

INTERCONNECTING MEMBER FOR ELECTRICALLY AND MECHANICALLY CONNECTING THE DISPLAY BOARD OF A MICROELECTRONIC CALCULATOR TO THE MAIN LOGIC CIRCUIT BOARD THEREOF

Roger D. Lang, 5175 Thorntree, Irvine, Calif. 92664; Philip J. Thomas, 3952 Patrick Henry Place, Agoura, Calif. 91301; and John A. McAllister, 26661 Las Tunas, Mission Viejo, Calif. 92675

Filed Jan. 27, 1975, Ser. No. 544,381

Term of patent 14 years

Int. Cl. D13—03

U.S. Cl. D26—1 A

FIG. 1 is a top left perspective view of an interconnecting member for electrically and mechanically connecting the display board of a microelectronic calculator to the main logic circuit board thereof;

FIG. 2 is a right side elevational view thereof;

FIG. 3 is a rear elevational view thereof;

FIG. 4 is a bottom plan view thereof;

FIG. 5 is a sectional view thereof, taken along line 5—5 of FIG. 3.

We claim:

The ornamental design for an interconnecting member for electrically and mechanically connecting the display board of a microelectronic calculator to the main logic circuit board thereof, as shown and described.
